UNITED STATES PATENT OFFICE.

JOHN VAUDREUIL, OF MILWAUKEE, WISCONSIN.

BATH-TUB.

1,246,190.

Specification of Letters Patent. Patented Nov. 13, 1917.

Application filed February 12, 1917. Serial No. 148,012.

To all whom it may concern:

Be it known that I, JOHN VAUDREUIL, a citizen of the United States, and resident of Milwaukee, in the county of Milwaukee and State of Wisconsin, have invented certain new and useful Improvements in Bath-Tubs; and I do hereby declare that the following is a full, clear, and exact description thereof.

10 This invention relates to bathroom fixtures, more particularly to new and improved construction in bath tubs.

The primary object of the invention is to provide a bath tub having an improved arrangement of spray pipes whereby the user may spray water or other liquids upon himself while seated within the tub.

A secondary object is to provide a tank in connection with the improved tub which is so constructed that it may contain salt for mixing with the water which flows into the interior of the tube and thereby supply the user with a salt bath.

With these and other objects in view, the invention resides in the novel features of construction, combination and arrangement of parts which will be hereinafter more specifically described and claimed.

In the drawings:—

30 Figure 1 represents a side elevation of a bath tub constructed in accordance with my invention, certain parts being broken out to more clearly show the construction thereof.

35 Fig. 2 is a central vertical sectional view through certain parts of the invention.

Fig. 3 is a detail vertical section showing a slightly modified form of my invention.

Referring now more particularly to the 40 several figures of the drawing wherein similar reference characters indicate like parts in all of the views, the numeral 1 denotes a bath tub of any ordinary or preferred construction, the same having the

45 usual feet 2 for spacing it above the floor. In carrying out the invention, I provide the upright wall 3 of the tub with a plurality of rows of openings, a pair of said rows designated by the numerals 4 and 5 being arranged

50 substantially parallel to each other and horizontally, while the other rows 6 are disposed vertically and between the rows 4 and 5. It will be noted that all of these rows of openings are positioned at one end of the 55 tub, preferably that remote from the end in which the water ordinarily enters. The

rows 5 are continued as shown in 5' from the first mentioned end to the latter end of the tub.

A plurality of spray pipes 7, 7' and 8 are 60 secured to the outer surface of the wall 3, preferably being formed integrally with the tub and of the same material. These spray pipes communicate with the rows of openings and provide means for conveying 65 water from the source of supply to the interior of the tub, said water being delivered in the form of a fine spray as in the case of an ordinary overhead shower. In Fig. 1 it will be seen that the pipe 7 communicates 70 with the rows of openings designated by the numerals 5 and 5' and the pipe 7' is connected with the openings 4, while the pipes 8, which are arranged substantially vertically, communicate with the rows of openings 6. All of these pipes are connected 75 with each other so that the water flows from the inlet end of the pipe 7 throughout the interior of all the other pipes, and said water is forced from all of the openings in 80 the wall 3 with equal force.

A supply tank 9 is preferably used in connection with the other features of my invention, said tank being usually mounted at the inlet end of the tub, and preferably 85 formed integrally therewith as shown in Fig. 2. The bottom of the tank is provided with an outlet opening 10 through which the water is conveyed from the tank to the pipe 7 by means of a valved pipe 11, the 90 valve in which is of ordinary construction, the plug 12 having the usual opening 13, the flow of water therethrough being controlled by a handle 14 connected to said plug. Hot and cold water enters the top of the tank 95 9 through the usual hot and cold water pipes designated broadly by the numeral 15, the flow from which is controlled by one or more valves connected to the handle or handles 16. 100

From the foregoing description it will be seen that the hot and cold water after entering the tank 9 is thoroughly mixed and distributed at the proper temperature through the spray pipes and into the tub, the flow 105 from the tank 9 being controlled by the above mentioned valve in the pipe 11. If it is considered desirable, water may be run directly from the hot and cold water pipes 15 directly to the inlet pipe 11 below the valve 110 therein without passing through the tank 9. This is accomplished by providing a

three way valve 25 between the valves in the hot and cold water pipes and the inlet of said tank as shown in Fig. 3. One part of this valve communicates with the inlet pipe 5 of the supply tank, another being connected with the pipes 15 and a third with a branch pipe or by-pass 26. This branch pipe communicates with the pipe 11 below the valve therein, thus cutting out the supply tank 10 entirely.

Under certain conditions it is desired that salt or other chemicals be added to the water in which a person is bathing. In such a case the ordinary prepared sea salt or other chemicals are placed in the tank 9 through a supplemental inlet opening 17, the same being normally closed by a screw cap 18. A foraminous plate 19, preferably of wire gauze, covers the opening 10 in the bottom 15 of the tank and prevents the salt or like matter passing through the opening in a solid form. It is obvious that as the water passes through the tank, more or less of the salt will be dissolved and carried with this water 20 when it enters the bath tub. This arrangement provides a very simple method of evenly distributing salt throughout the water in which a person may wish to bathe. If the water which is being passed through 25 the supply of salt in the tank does not dissolve a sufficient amount of said salt, the valve of the pipe 11 may be closed and the salt contained in the tank allowed to remain therein with a sufficient quantity of water, 30 for a considerable length of time before the tub is to be used for bathing. Or a person may take an ordinary bath with plain water by turning the three way valve 25 in the proper direction to permit the water to flow 35 through the branch pipe 26. After a sufficient quantity of salt is dissolved, the valve 25 may be closed and the valve in the pipe 11 opened to permit the salt solution to flow 40 through the openings in the wall of the tub 45 in the same manner that the plain water is forced therefrom. This solution may be forcibly ejected from the openings in the wall of the tub by means of compressed air which is supplied to the tank from an apparatus which will be later particularly described.

Still another use may be made of this supply tank 9, for instance, if a person bathing desires to spray himself with perfumed water, 50 or the like, the same is placed in said tank through the opening 17. Before, however, placing this perfumed water within the tank, the plug 12 is rotated to close the pipe 11, and after it has been placed therein, compressed air is added in order that the liquid 55 may be forcibly ejected from the various openings in the wall of the tub in the form of fine spray or vapor. In the present instance the means for supplying this compressed air is mounted directly upon the tank

9 and consists of an ordinary compressed air pump 20, the lower end of which is screw threaded for engagement with the screw threads in the socket of a boss 21, the bottom of said socket communicating with 70 the interior of the tank by means of a passageway 22. Upon reciprocation of the plunger of said pump 20, the air under sufficient pressure will be forced into said tank 9 and thereby accomplish the desired purpose.

From the foregoing description taken in connection with the accompanying drawing, it will be seen that a very simply constructed bath tub has been produced which is provided 80 with novel means for passing various soluble materials and the like to the water as it is sprayed from the openings in the wall of the tub. The peculiar arrangement of the spray openings permits the person's body to 85 be thoroughly sprayed while he is seated within the tub, thereby doing away with the necessity of providing an additional shower with a tub of ordinary construction.

What is claimed:—

1. An apparatus of the class described comprising a receptacle having a plurality of substantially parallel horizontally disposed rows of openings extending through the wall thereof at one end, said receptacle also having a plurality of substantially parallel vertically disposed rows of openings positioned between said horizontal rows, a plurality of horizontally and vertically arranged spray pipes communicating with said openings and 100 connected to each other, and means for supplying liquid to said pipes.

2. The combination with a receptacle of a liquid supply tank, a valved outlet from the bottom of the tank and communicating with the interior of the receptacle, a foraminous plate covering the outlet in the bottom of the tank, and a valved inlet into said tank whereby to control the flow of liquid thereto, said supply tank also having a supplemental filling opening therein.

3. An apparatus of the class described comprising a receptacle, a supply tank fixed to the wall thereof, a socketed boss on said tank, the socket therein communicating with the interior of the tank, a compressed air pump having one end disposed in said boss, a valved inlet into the upper end of the tank and a valved outlet from the bottom of the tank to the interior of said receptacle, said tank also having a supplemental filling opening in its top.

4. An apparatus of the class described comprising a receptacle, a supply tank fixed to the wall thereof, an inlet control valve connected to the top of the tank, a three-way valve disposed between said control valve and the tank, a valved outlet pipe from the bottom of the tank to the interior of said receptacle, a by-pass pipe extending from 130

the three-way valve to said outlet pipe, a socketed boss on said tank, the socket therein communicating with the interior of the tank, and a compressed air pump having one end disposed in said boss, said tank also having a supplemental filling opening in its top.

5 In testimony that I claim the foregoing I

have hereunto set my hand at Milwaukee, in the county of Milwaukee and State of Wisconsin, in the presence of a witness.

JOHN VAUDREUIL.
